UNITED STATES PATENT OFFICE

144,276

DESIGN FOR A CIGAR COUNTER HUMIDOR

Robert B. Wemyss, Louisville, Ky.

Application October 14, 1944, Serial No. 115,774

Term of patent 7 years

(Cl. D85—2)

To all whom it may concern:

Be it known that Robert B. Wemyss, a citizen of the United States, residing in Louisville, county of Jefferson, State of Kentucky, has invented a new, original, and ornamental Design for a Cigar Counter Humidor, of which the following is a specification, reference being had to the accompanying drawing, forming part thereof.

The figure is a perspective view of a cigar counter humidor showing my new design.

I claim:

The ornamental design for a cigar counter humidor, substantially as shown and described.

ROBERT B. WEMYSS.
